UNITED STATES PATENT OFFICE.

WILLIAM H. O'KEEFE, OF LOCKPORT, NEW YORK.

SHADE-ROLLER.

SPECIFICATION forming part of Letters Patent No. 730,292, dated June 9, 1903.

Application filed June 6, 1902. Serial No. 110,526. (No model.)

To all whom it may concern:

Be it known that I, WILLIAM H. O'KEEFE, a resident of Lockport, in the county of Niagara and State of New York, have invented certain new and useful Improvements in Shade-Rollers; and I do hereby declare the following to be a full, clear, and exact description of the invention, such as will enable others skilled in the art to which it appertains to make and use the same.

My invention relates to an improvement in shade-rollers, the object of the invention being to provide improved means for protecting the spring against possibility of tacks being driven into the spring-cavity to interfere with the perfect operation of the spring.

With this object in view the invention consists in certain novel features of construction and combinations and arrangements of parts, as will be more fully hereinafter described, and pointed out in the claims.

In the accompanying drawings, Figure 1 is a view in section, illustrating my improvements. Fig. 2 is a view in cross-section of the same, and Fig. 3 is a view illustrating a modification.

1 represents an ordinary wooden shade-roller provided in one end with a bore of suitable length to receive a spring 2, secured at one end to a block 3 and at its other end to a rod or shaft 4, mounted to turn in the spring and to wind the spring thereon, the block 3 being secured in the bore by a nail or tack driven through the roller and into the block.

35 The shaft 4 is provided with a notched hub 7 for the engagement of dogs 8, pivotally supported by a plate 9, secured to the roller. The operation of these ratchet devices being well known, further description thereof is unnecessary. This bore in the roller must be sufficiently large to accommodate the spring, and hence but a thin casing of wood covers the spring and necessitates the employment of short tacks to secure the shade to the roller 45 and has been the cause of the ruin of a vast number of rollers by reason of the employment of a tack of too great length, which enters the spring-cavity and interferes with the perfect operation of the spring, and it is the

purpose of my invention to provide means for protecting the spring against possibility of tacks being driven therein, as will now be explained. In the bore and surrounding spring 2 I force a metal tube 6, which is of sufficient length to protect the entire spring and prevent possibility of tacks being driven therethrough. This tube 6 will upset any tacks driven thereagainst, and hence will absolutely overcome the well-known objection to wooden rollers, as above set forth.

I may dispense with block 3 and secure the end of the spring 2 directly to tube 6, as shown in Fig. 3, enabling the spring to be secured in the tube and both inserted in the bore of the roller together.

A great many other slight changes might be made without departing from my invention, and hence I do not wish to be limited to the precise construction set forth, but consider myself at liberty to make such other slight changes and alterations as fairly fall within the spirit and scope of my invention.

Having fully described my invention, what I claim as new, and desire to secure by Letters Patent, is—

1. As a new article of manufacture, a wooden shade-roller having a cylindrical cavity in one end, a metal tube secured in said cavity and lining the wall thereof, a spring in said tube and connected at one end therewith, and a shaft entering said spring and having the other end of the latter secured thereto.

2. As a new article of manufacture, a shade-roller having a cavity in one end, a metal tube fixed in said cavity and constituting a lining for the latter, a plug secured in said cavity and entering one end of the metal tube, a spring in the tube secured at one end to said plug, and a shaft entering the other end of the spring and secured thereto.

In testimony whereof I have signed this specification in the presence of two subscribing witnesses.

WILLIAM H. O'KEEFE.
